UNITED STATES PATENT OFFICE.

JOHN LINCOLN PERKINS, OF SABETHA, KANSAS.

OIL-BURNER.

1,350,466.

Specification of Letters Patent. Patented Aug. 24, 1920.

Application filed May 13, 1919. Serial No. 296,752.

To all whom it may concern:

Be it known that I, JOHN LINCOLN PERKINS, a citizen of the United States, residing at Sabetha, in the county of Nemaha and 5 State of Kansas, have invented certain new and useful Improvements in Oil-Burners; and I do declare the following to be a full, clear, and exact description of the invention, such as will enable others skilled in the 10 art to which it appertains to make and use the same; reference being had to the accompanying drawings, and to the letters and figures of reference marked thereon, which form a part of this specification.

15 This invention relates to improvements in burners particularly for oil while it is equally adapted for use in burning natural gas.

The invention has for its object, among 20 other things to provide for admitting or taking the air laterally into the burner up through the bottom from the outside to the center, thus providing for perfect combustion and accordingly promoting, or making 25 effective, the heating action.

A further object is to provide for directing the flame directly upward for more fully utilizing the heat thereof, as called for in upright-boilers or heaters of the pipe-coil 30 type.

A still further object is to provide for spreading the flame, as required to render more effective the heating action as in cook stoves.

35 A still further object is to provide for conducting or passing the air in an undulatory or wave-like manner, into the burner, or with respect to the interior of the latter, that shall obviate any noisy action therein 40 from such passage of air.

A still further object is to provide for generating the oil or fluid as admitted to the burner, thus providing for a generating action whether the flame be turned up high or 45 down low, the same also aiding combustion and adapting it for burning natural gas.

A still further objects is to provide for throwing the flame in any one given direction as circumstances may require particu- 50 larly in cook-stoves.

The invention therefore consists of cer- 55 tain instrumentalities and features of construction, substantially as hereinafter fully disclosed and defined by the appended claim.

In the accompanying drawing is illus- trated the preferred embodiment of my in-

vention wherein it will be understood that various changes and modifications as to the detailed construction and arrangement of parts may be made without departing from 60 the spirit or scope of the claim, and in which drawing—

Figure 1 is a plan view of my burner, with one deflector flame member or baffle displaced and positioned to one side thereof. 65

Fig. 2 is a sectional view also of a like flame deflector member for directing the flame in any one given direction.

Fig. 3 is a vertical section of my burner with the first-referred to flame deflector or 70 baffle member in position on the burner.

Fig. 4 is a plan view of the burner with the top or flame member displaced.

Fig. 5 is a plan view of the burner with the single - given - direction flame - directing 75 member in position thereon.

Fig. 6 is a plan view of the spreader member.

In carrying out my invention, I suitably cast a base or oil-holding member or pan, 80 designated generally as 1, preferably circular, with the oil-holding portion or pan proper 2 somewhat conical, the same tapering downwardly, with an upwardly-projecting oil inlet or intake 3 upon its interior 85 surface with drilled oil-openings therein and at which point connection is made with the oil-pipe (not shown) upon its outside. The base or oil holding member 1 has an annular flange-like extension portion 4 upon its 90 perimetrical surface, which is provided with a circular arrangement of air-ingress open- 95 ings or orifices 5, more or less in number and size according to the capacity of the heating or cooking utensil or boiler to which 100 it is to be applied. The circular flange-like portion or extension 4 has itself a circum- 105 ferential rim 6, stepped in transverse section, as at 7, to provide for the application there- to, upon the less-diametered portion thereof, of a band 8, of preferably galvanized iron, with its upper edge fitting under the greater diameter of the stepped portion, adapted to elevate the burner about two inches above the plane of its bottom surface and serves 110 as a packing ring for the burner, said circum- 115 ferential rim has a circular groove 9 in its upper surface, the purpose of which will appear later.

Complemental of the base or oil-holding member 1 is a top circular casting or member 1^a rounded upwardly toward its circum-

ferential marginal edge, which is received in the circular groove 9 of the base member or casting 1, inwardly or toward its center, thus dishing its inner or underneath surface and 5 combining with said base member or casting to suitably constitute the air and vapor mixing chamber 10. The disposing of the circumferential edge of the top member 1^a within the groove 9 of the base-member prevents 10 the casual or accidental displacement of the top member from said base member as well as forms an overlapping gas-proof joint at that point as at 11.

The upper edge of the pan or member 1, 15 which is preferably outwardly flared or flanged, as at 12, has an upstanding rib or ledge 13 thereon, and the top member or casting 1^a has around an oblong flame opening or orifice 14 therein, upon its inner or 20 underneath surface, a downwardly projecting rib or ledge 15 conforming, of course, to the general oblong outline of said flame-opening or orifice, which rib or ledge 15 is, however preferably somewhat reduced at its 25 end-portions than the other portions thereof, as at 15^a. It will be observed that the relative arrangement of the ledges or ribs 13 and 15 is such that the air admitted through the air-intake openings or orifice 30 5, will take an undulatory course, *i. e.*, will pass over one rib or ledge and down under the other, the edges of said ledges or ribs being out of alinement with each other, whereby otherwise direct-draft, caused by 35 the action of the flame, will be neutralized by the heating action of the ledges or ribs upon the air contacting therewith, as is apparent, thus stopping the noise or "blouring" otherwise usually resulting with burners as heretofore constructed.

A generator 16, of the general construction as shown, being approximately conical and hollow with laterally opening conduits or passages 16^a in its flared bottom edge and 45 communicating with its interior, is positioned over, and receiving the oil or natural gas-supply from the supply-pipe before referred to, thus providing for a generating action either when the flame is turned higher 50 or lower.

A spreader member 17 of the construction substantially as disclosed, the same having an intermediate upraised imperforate portion 17^a, with downturned end-terminals

17^b, said terminals having projecting therefrom preferably downwardly tapered studs 17^c which are received in notched upstanding studs or posts 18 fixed to, or integral with the upper member or casting 1^a, opposite the ends of the oblong flame-orifice 14 60 of the latter, with the lower edges of the end-terminals 17^b resting upon said upper member. With the spreader member 17 thus positioned upon the upper casting, it will be seen that the lateral resultant openings 19 of the spreader member 17 will provide for delivering the flame therethrough laterally each way as called for upon applying the burner, especially to a cook-stove, as will be appreciated. 70

A second spreader member or hood 20, is herein employed similar in construction to the spreader 17, with the exception, only what may be termed as one side thereof is left open, as at 20^a, this form of spreader member being used only when it may be desired to throw or direct laterally the flame in any one direction, the upper casting or member being shiftable or rotatable for the requisite presentation of its lateral or side 80 opening for this purpose as will be readily apparent.

Of course it will be understood that in using the burner without the spreader members the flame is directed straight upwardly 85 as called for in applying it to an upright boiler or the pipe-coil type of heater.

Having fully described the invention, I claim—

A burner of the type described, including 90 the pan or base-section having a perimetrical flange-like portion provided with air- orifices and with a circular groove, said base-section also having an upstanding ledge, at its upper edge, and an upper complementary superposing section having its outer marginal edge received by said groove, said base-section and superposing section having interior ledges or ribs with their upper and lower edges arranged in planes 95 100 above and below each other respectively.

In testimony whereof, I affix my signature, in presence of two witnesses,

JOHN LINCOLN PERKINS.
